CLOSURE FASTENER

Carl E. Bashe, Minneapolis, Minn.

Application August 25, 1938, Serial No. 226,711

5 Claims. (Cl. 292—342)

My invention relates to closure fasteners and has for an object to provide a fastener particularly adaptable for use in conjunction with windows having double hung sash.

5 Another object of the invention resides in providing a closure fastener which will be simple in construction.

A still further object of the invention resides in providing a closure fastener which will be 10 inexpensive to manufacture.

An object of the invention resides in providing a closure fastener which may be easily applied to the structure with which it is to be used and which will not readily get out of order.

15 An object of the invention resides in providing a closure fastener which will be rattle proof.

Another object of the invention resides in providing a fastener by means of which the opening of the sash may be limited to a predetermined 20 amount.

25 A still further object of the invention resides in providing a closure fastener having a mounting and a stop carried by said mounting and in constructing the stop detachable from the mounting to permit of complete opening of the sash.

30 Another object of the invention resides in attaching the mounting to one of the stiles of one of the sash and in constructing the mounting of dimensions such that the mounting projects outwardly from the stile to which it is attached an amount less than the clearance between the said stile and the meeting rail of the other sash so that the said second named sash may slide past 35 the mounting.

Another object of the invention resides in constructing the stop with attaching means disposed wholly within the confines of said mounting.

Another object of the invention resides in 40 constructing the mounting from a plate U-shaped in form and having an opening therein extending through an edge thereof and in further having the marginal portion of the plate adjacent said opening turned outwardly therefrom to form two spaced parallel tongues and to leave co-planar flanges adjoining said tongues and providing a base.

A feature of the invention resides in detachably securing the stop to said tongues.

45 Another object of the invention resides in constructing the stop with a bearing surface adapted to engage the surface to which the mounting is applied and within the opening formed in said mounting.

50 Other objects of the invention reside in the

novel combination and arrangement of parts and in the details of construction hereinafter illustrated and/or described.

In the drawing:

Fig. 1 is a vertical sectional view through a 5 window illustrating the application of my invention thereto.

Fig. 2 is a fragmentary elevational view of a door and a door frame illustrating the application of my invention thereto.

10 Fig. 3 is a perspective view of the closure fastener detached from the window or door.

Fig. 4 is a perspective view of the mounting.

Fig. 5 is a perspective view of the stop.

15 Fig. 6 is a plan view of the structure shown in Fig. 3.

Fig. 7 is a fragmentary cross sectional view taken on line 7—7 of Fig. 1.

20 For the purpose of illustrating my invention, I have shown in Fig. 1 a portion of a window 10 having a frame 11 in which is slidably mounted a pair of double hung sash 12 and 13.

The frame 11 consists of vertical frame members 14 which have secured to them stops or runners 15, 16 and 17 between which tracks 25 18 and 19 are formed and in which the sash 12 and 13 slide.

25 The sash 12 includes stiles 21 and a meeting rail 22 together with such other parts as are customarily found in sash. The sash 13, similarly includes stiles 23 and a meeting rail 24 which is adapted to engage the rail 22 to close the sash when the rails 22 and 24 are opposite one another. As will be noted in Fig. 1, the corner 25 of the rail 24 has a certain amount of clearance with reference to the stile 21 of sash 12 30 which is brought about by the use of the stop or runner 16. This clearance has been designated by the reference numeral 26 and is utilized with my invention as will be presently more fully 35 described.

40 My invention proper consists of a mounting 27 which is adapted to be attached to the stile 21 of sash 12 and which has detachably secured to it a stop 28 which is adapted to engage sash 45 13 and to limit relative sliding movement of the sash. These parts will now be described in detail.

45 The mounting 27 is constructed from a blank of sheet metal which is U-shaped in form to provide two legs 32 and 33 and a connecting portion 34 therebetween. By means of this construction an opening 29 is formed in the center of the blank extending through one edge thereof. The marginal portion 31 of the blank extending about 50

55

the opening 29 is turned outwardly therefrom, as best seen in Fig. 4. This forms two tongues 35 and 36 which extend along the legs 32 and 33 and flanges 37 and 38 issuing therefrom. The flanges 37 and 38 lie in the plane of the blank from which the mounting is constructed and form a base for attaching the mounting to the stile 21. In similar manner the marginal portion 31 may be turned up at the rear of the opening 29 to form an abutment 39 and a flange 41 connected therewith. Both of the tongues 35, 36 and the abutment 39 lie in continuation and likewise the flanges 37, 38 and 41 lie in a single plane. The tongues 35 and 36 are arranged in converging relation so that the same form a dove-tailed slot therebetween. The flanges 37 and 38 are constructed with holes 42 through which suitable screws 43 (Fig. 1) may be inserted for attaching the mounting to the stile 21.

20 The stop 28 is preferably constructed of some resilient material such as rubber or any of the similar compositions now used in place thereof. This stop comprises a body 44 having spaced parallel lateral surfaces 46, a bearing surface 47 and an upper surface 48. The surface 48 converges with respect to the bearing surface 47 to form a wedge 49 at the toe end of the body 44. At the heel end of this body the same is constructed with two grooves 51 which are parallel to one another and which toe inwardly to form a dove tail adapted to be inserted into the dove-tailed groove formed by the tongues 35 and 36. The tongues 35 and 36 are adapted to be received within the grooves 51 and the stop 28 may be slid longitudinally along the tongues 35 and 36 until movement of said stop is arrested by means of abutment 39. In the construction of the mounting 27, the height of the tongues 35, 36 and 39 is made less than the clearance 26 between the rail 24 of sash 13 and the stile 21 of sash 12. This permits of the sliding of the sash 13 past the mounting 27 whereby the window may be operated in the customary manner when the stop 28 is removed.

45 In the installation of the device the mounting 27 is attached to the stile 21 of sash 12 by means of the screws 43 which extend through the holes 42 of the flanges 37 and 38 and are screwed into the stile 21. Mounting 27 is so arranged that the abutment 39 is uppermost and so that the opening 29 opens downwardly. Due to the construction of the said mounting, after the same has been applied, the sash may be slid relative to one another without interference with the mounting 27. When it is desired to limit relative sliding movement of the sash, stop 28 is applied to the mounting 27 by sliding the same along the tongues 35 and 36. The body 44 of said stop is of a height at its heel end greater than the clearance 26 so that, when the windows are moved relative to one another, the corner 25 of rail 24 of sash 13 engages the converging surface 48 of the wedge 49 and wedges the sash tightly against the runners 15 and 17, thus limiting opening movement of the sash. Such movement tends to force the body 44 along the tongues 35 and 36 and toward the abutment 39. This abutment prevents disengagement of the stop from the holder and prevents further movement of the sash.

70 It will be noted that the bearing surface 47 of the body 44 of stop 28 bears directly against the surface of the stile 21 throughout its entire extent. By means of this construction, rattling of

the device is entirely prevented. Should the mounting 27 become loose, the stop 28, being disposed directly between the two sash and without any intervening structure, would positively engage both parts and prevent relative movement therebetween. Any pressure applied to the surface 48 of the body 44 of stop 28 tends to spread out the material of the said stop and particularly at the grooves 51 which causes outward movement of the mounting 27, thereby urging the same away from the surface of the stile 21 and thus taking up the play which might have resulted in this mounting becoming loose. In this manner rattling is prevented, even though the mounting 27 may become loose.

15 In Fig. 2 I have shown my invention used as a door stop. In this figure a door frame 61 is shown and to which is hingedly connected a door 62 by means of hinges 63. The floor of the room, in which the door and frame is installed, is indicated by the reference numeral 64. In using my invention in conjunction with the door 62, the mounting 27 is attached to the floor and the stop 28 is secured to the mounting in a manner such as to engage the lower corner 65 of the door 62 when the same is swung up to the desired ultimate position. On removal of the stop 28 the door may swing free of the mounting 27 and thus function in its ordinary manner.

20 My invention is highly advantageous in that an extremely simple and practical construction is provided, whereby the opening of windows may be limited. With my invention the stop can readily be removed and when once removed the window operates entirely in the same manner as without the fastener. My invention can be constructed at a nominal cost and is easy to install. My device is so simple that the operator can readily understand the method of use and no experience or intricate instructions are needed to 35 explain the method of operation. Should the stop fall out of the mounting the same would not prevent operation of the sash. My invention will not mar or injure the closure with which it is to be used. The window utilizing my improved 40 closure fastener becomes entirely rattle proof when the window is opened and even if the mounting becomes loose, rattling is still prevented.

45 Changes in the specific form of my invention, as herein disclosed, may be made within the scope of what is claimed without departing from the spirit of my invention.

50 Having described my invention, what I claim as new and desire to protect by Letters Patent is:

55 1. A closure fastener comprising a mounting for attachment to the surface of an object with which the fastener is to be used, said mounting having an opening in the center thereof and tongues extending along said opening, a stop having a bearing surface adapted to engage the surface on which the mounting is attached and means on the opposite side of said stop for engagement with said tongues for guiding said stop for sliding movement along said tongues and over said surface.

60 2. A closure fastener comprising a mounting constructed from a plate U-shaped in form and having an opening therein extending through an edge of the plate, said plate having the marginal portion thereof at said opening turned outwardly therefrom to form two spaced parallel tongues and to leave coplanar flanges forming a base, means for attaching said flanges to the surface 65 of the structure with which the fastener is to be 70 75

used and a stop having a bearing surface adapted to rest upon the surface on which said mounting is disposed and within the opening in said mounting, means for detachably securing said stop to said tongues and means extending through said flanges for attaching the mounting to the structure with which it is to be used.

5. A closure fastener comprising a mounting constructed from a plate U-shaped in form and having an opening therein extending through an edge of the plate, said plate having the marginal portion thereof at said opening turned outwardly therefrom to form two spaced parallel tongues and to leave coplanar flanges forming a base, and

10 a stop having V-shaped grooves on opposite sides thereof adapted to receive said tongues and to hold the stop attached to said mounting thereby.

15 4. A closure fastener for application to a window having a frame formed with a runner and a pair of double hung sash slideable on opposite sides of said runner and provided with stiles and meeting rails, said closure fastener comprising a mounting constructed from a plate U-shaped in form and having an opening therein extending through an edge of the plate, said plate having the marginal portion thereof at said opening turned outwardly therefrom to form two spaced parallel tongues and to leave co-planar flanges forming a base, means for attaching said base

20 to the stile of one of said sash, said base and tongues extending outwardly from said stile an

amount less than the clearance between said stile and the meeting rail of the other sash, a stop having V-shaped grooves adapted to receive said tongues for slidably attaching said stop to said mounting, said grooves and tongues being parallel with said stile, said stop projecting outwardly beyond the clearance between said stile and the meeting rail of the other sash and serving to engage said meeting rail and to be urged into movement along said tongues through engagement with said meeting rail, and means for limiting the sliding movement of said stop to cause the same to limit the movement of the sash.

10 5. A closure fastener for application to a window having a frame formed with a runner and a pair of double hung sash slideable on opposite sides of said runner and provided with stiles and meeting rails, said closure fastener comprising a mounting adapted to be attached to one of the stiles of one of said sash and to project outwardly beyond said stile an amount less than the clearance between said stile and the meeting rail of the other sash, a stop carried by said mounting and formed in the shape of a wedge provided with two friction surfaces, said mounting holding said stop with one friction surface in engagement with the stile to which the mounting is attached and the other surface for engagement with the opposite part of the other sash.
